(57) **CLAIM**

The ornamental design for a mower deck scraper, as shown.

DESCRIPTION

FIG. 1 is a perspective view of a mower deck scraper showing my new design as viewed from a working end; FIG. 2 is a side view thereof, the opposite being a mirror image;

FIG. 3 is a top side view thereof;

FIG. 4 is a bottom side view thereof;

FIG. 5 is an end view on an enlarged scale as viewed from an operator end; and,

FIG. 6 is an end view on an enlarged scale as viewed from the working end.

The broken lines illustrate environmental subject matter that forms no part of the claimed design.

1 Claim, 4 Drawing Sheets
